UNITED STATES PATENT OFFICE

158,830

STEAM TABLE

Nelson P. Bard, Chagrin Falls, Ohio

Application February 6, 1948, Serial No. 144,329

Term of patent 3½ years

(Cl. D49—1)

To all whom it may concern:

Be it known that I, Nelson P. Bard, a citizen of the United States, residing at Chagrin Falls, county of Cuyahoga, and State of Ohio, have invented a new, original, and ornamental Design for a Steam Table, of which the following is a specification, reference being had to the accompanying drawings, forming a part thereof.

Fig. 1 is a front perspective view of a steam table, showing my new design.

Fig. 2 is a rear perspective view thereof.

I claim:

The ornamental design for a steam table, as shown.

NELSON P. BARD.
